UNITED STATES PATENT OFFICE.

THOMAS BEST, OF DETROIT, MICHIGAN.

BURIAL-CASE.

1,377,656.

Specification of Letters Patent. Patented May 10, 1921.

Application filed July 6, 1920. Serial No. 394,109.

To all whom it may concern:

Be it known that I, THOMAS BEST, subject of the King of Great Britain, residing at Detroit, county of Wayne, State of Michigan, have invented a certain new and useful Improvement in Burial-Cases, and declare the following to be a full, clear, and exact description of the same, such as will enable others skilled in the art to which it pertains to make and use the same, reference being had to the accompanying drawings, which form a part of this specification.

My invention relates to improvements in burial cases and their method of manufacture.

The object is to provide an inexpensive burial case of simple construction that will be proof against the action of water.

In the drawings,—

Figure 1 is a perspective of my improved case.

Fig. 2 is a longitudinal vertical section.

Fig. 3 is a vertical section of a modified form.

Fig. 4 is an elevation of a cover of my case in the modified form.

My new and improved burial case comprises two separate cases, or boxes, the outer of which is indicated as *a*, and is a wooden case water-proofed in any suitable manner, such as by creosoting the same or by boiling the material in pitch or tar. The inner case, indicated as *b*, is adapted to be received within the outer case and is constructed sufficiently small to provide an intervening space between the walls of the two cases. This case *b* is provided with a lid or cover *b*². The case *a* is provided with a lid or cover *a*². The inner case *b*, as shown in Fig. 2, is adapted to be used as a receptacle for a casket *c*.

In the modification shown in Figs. 3 and 4 the inner case *b* is adapted to serve as a casket intended to receive the body direct.

In this use of the inner case, at one end of the lid or cover is provided a transparent window *d* provided with a cover plate *e* adapted to be received in such recess to form a protective covering for the window.

These cases are constructed in a substantial manner. They may be joined together at the edges by tongue-and-groove or in such other method as is thought desirable.

In the further assembly of the provided cases consists the principal feature of my invention.

I pour into the bottom of the outer case *a* a layer *f* of boiling pitch or tar or other asphaltum material, which layer will serve to form a bottom layer of a thickness equal to 60 the provided space between the two cases of water-proof material, any tar product or other similar substance being satisfactory. The inner case *b* is then placed within the outer case, the bottom thereof being separated from the bottom of the outer case by the layer of tar or pitch material. When the cover has been placed on the inner case, tar or pitch is poured over and around the sides thereof forming a side wall layer of tar 70 between the inner and outer cases and completely covering the top of the case until the inner case *b* is completely incased and insealed in tar; the outer case being completely filled with this asphalt product the 75 cover *a*² is then secured to the outer case, completing the operation.

It will be apparent that when the above-described operation is completed we have an inner case or receptacle adapted to receive either the body or a casket, which inner case is completely incased or sealed up in a tar covering, that the inner case thus insealed is then disposed within an outer box for further protection.

What I claim is:

1. The method of constructing a burial case which consists in providing a creosoted outer box, an inner box adapted to be received therein spaced therefrom, pouring a 90 heated tar product into the outer box so as to form a tar layer over the bottom thereof, positioning said inner box thereon, pouring a heated tar product around the inner box so as to completely fill the space between the inner and outer box, pouring such heated tar product over the cover of such inner box so as to completely inseal and incase said inner box, placing the cover of said outer box in position.

2. The process of constructing a burial case which consists in providing two boxes, an inner box adapted to fit within an outer box spaced therefrom, said outer box constructed of material which has been boiled 105 in creosote, pouring a heated tar product in the larger of said boxes so as to completely cover the bottom thereof with a layer of said tar product, placing said inner box within said outer box supported on said tar layer, 110 pouring heated tar around said inner box so as to fill the space between said inner

- and outer box to within a short distance of the top of the wall of said inner box, placing the cover on said inner box after the casket has been placed therein, pouring heated tar 5 over and around said inner box so as to fuse with the tar previously poured around the wall thereof and completely inseal said inner box in a tar layer, placing the cover on said outer box.
- 10 3. The method of constructing a burial case consisting in pouring into a provided outer box a thick layer of a tar product so as to completely cover the bottom thereof, inserting a smaller box within such outer 15 box spaced from the walls thereof, supported from the bottom wall by such tar layer, pouring further tar in the provided space between the walls of such cases so as to completely fill the same around and over the top 20 of such inner case until the same is com-

pletely incased and insealed within such tar, securing a cover to such outer case.

4. The method of constructing a burial case which consists in providing two wooden boxes one adapted to fit interior the other 25 spaced from the walls thereof, such boxes provided with removable covers, pouring a layer of boiling pitch or tar within the larger of said boxes so as to completely cover the bottom thereof, inserting the smaller 30 box within the larger one upon such tar layer, placing the cover on such inner box, pouring further tar in the outer box over and around such inner box until the inner box is completely incased and insealed in 35 tar, securing the cover to such outer box.

In testimony whereof, I sign this specification.

THOMAS BEST.
